UNITED STATES PATENT OFFICE.

GODFREY L. CABOT AND JAMES J. CABOT, OF BOSTON, MASSACHUSETTS.

APPARATUS FOR CONDENSING GAS UNDER HIGH PRESSURE.

1,225,574.

Specification of Letters Patent. Patented May 8, 1917.

Application filed October 26, 1914. Serial No. 868,680.

To all whom it may concern:

Be it known that we, GODFREY L. CABOT and JAMES J. CABOT, citizens of the United States, residing at Boston, in the county of 5 Suffolk and State of Massachusetts, have invented certain new and useful Improvements in Apparatus for Condensing Gas Under High Pressure; and we do declare the following to be a full, clear, and exact 10 description of the invention, such as will enable others skilled in the art to which it app pertains to make and use the same.

This invention relates to new and useful 15 improvements in an apparatus for condensing gas but particularly natural gas under high pressure and the primary object of this invention is to provide an apparatus of this character which provides for the free and rapid flow of the liquefied gas and at the same time permits the ready escape of the 20 unliquefied gas.

Still another object of the invention resides in providing an improved cooling or liquefying chamber in which the unliquefied 25 gas is permitted to escape and aid in the cooling of the liquefied gas.

Still another object of the invention resides in providing a cooling system of the reverse order wherein gas is introduced into 30 the chamber from one end and liquefied as the same travels in the reverse direction to the cooling fluid, thus aiding in the condensation and retention of the liquefied gas in its cooled state.

Still another object resides in providing a 35 lagging for the various pipes and receptacles containing the liquefied gas, such lagging being of a non-conducting material and preferably non-combustible, whereby to retain the gas within the pipes and receptacles 40 at a predetermined freezing temperature.

Still another object of the invention resides in providing a device which is simple and durable in construction, comparatively 45 inexpensive to manufacture and one which will be very efficient and useful in operation.

In the accompanying drawings forming a part of this application;

Figure 1 is a side elevation of an apparatus constructed in accordance with our invention, parts being broken away and parts being disclosed in section;

Fig. 2 is a plan view thereof;

Fig. 3 is a detail section through the gas cooled chamber; 55

Fig. 4 is a transverse section as seen on line 4—4 of Fig. 3;

Fig. 5 is a vertical section through the water cooled chamber and side view of the worm therein; 60

Fig. 6 is a side elevation of a slightly modified form of the invention;

Fig. 7 is a detail section therethrough; and

Fig. 8 is a detail plan view of the same. 65

It is a well known fact that gas can only exist in a liquid state either by reason of intense cold or of being placed under great pressure, or both and in carrying out our invention we prefer to utilize both the cooling 70 and pressure systems. In describing the invention we shall refer to the drawings in which similar reference characters designate corresponding parts throughout the several views and in which 1 designates an inlet 75 pipe leading from any desired source (not shown) through which the natural gas enters the device. This inlet pipe is provided with a gate valve 2 beyond which is arranged a pressure regulator 3 and also 80 mounted in connection with this pipe 1 just beyond the pressure regulator 3 is a meter 4, the purposes of which appear obvious. This inlet pipe 1 terminates in a gas reservoir or chamber 5 which is provided for the purpose 85 of equalizing the pressure of the gas in view of a gas compressor 6 which has connection with this chamber or reservoir by means of a pipe 7. This compressor 6 is of the three stage type and is actuated by means of a gas 90 engine 8.

Arranged just beyond the engine 8 is a cooling chamber or tank 9 to which water is supplied by means of a pipe 10 leading from a centrifugal pump 11. The connection between this pipe and the cooler or chamber 9 is at the lower end of the latter and said pipe 10 continues onward and communicates with the water jacket of the engine 8 for supplying water to the latter. Drain pipes 100 12 lead from the upper portion of the chamber or tank 9 and the water jacket of the engine 8 so that the heated water therein may be drawn therefrom.

Leading from the compressor 6 is a pipe 105 section 13 which conducts the natural gas

under very high pressure to the tank or chamber 9 wherein said pipe 13 connects with a coil 14 extending the full height of said member 9. It will be noted that the 5 gas under pressure entering the cooling chamber 9 enters from the upper portion of the latter and is directed downwardly toward the lower end thereof while the cooling medium, water, enters from the lower 10 end of said chamber 9 and rises upwardly therethrough, being drained therefrom by the pipe 12 which leads from the upper end of said chamber. It is obvious with this 15 reverse system that the directing of the gas and water in reverse directions will tend to thoroughly cool the gas in the coil 14 and with a minimum amount of water or other fluid. Leading from the lower end of the coil 14 through the wall of the chamber 9 20 is an additional pipe section 15 which leads through the wall of a second cooling or liquefying chamber 16 which is disposed just beyond the chamber 9. This pipe section 15 connects the upper end of an additional 25 coil 17 which is suitably arranged in this chamber 16, the lower end of the latter connecting with a metallic receptacle or chamber 18. This latter chamber is, as indicated before, the liquefying chamber and this 30 liquefying process is effected through the medium of escaping unliquefied gas, or gas which cannot be liquefied. This gas is permitted to escape from the chamber 18 through a valve 19 which is arranged at the upper 35 portion of said receptacle or chamber 18 adjacent to one end thereof. The valve is provided with a manually operable means 20 which projects through the wall of the chamber 16 to be conveniently operated. 40 This escaping gas is adapted to travel upwardly through the chamber 16 and tends to cool the gas in the coil 17 thus tending to liquefy such gases therein as are not yet liquefied and retaining the gases which are 45 in a liquid state at a low temperature.

As will be seen from the drawings the compressed gas enters this receptacle 16 from the top thereof traveling through the bottom of the same before it makes its exit 50 therefrom but the escaping unliquefied gas which is used as a cooling medium to aid in the liquefaction tends to rise upwardly in said chamber. In order to force the escaping gas to pursue a course of great length 55 through this chamber 16, the latter is provided with a plurality of horizontal division walls 21 between each pair of which is received a twist or section of the coil 17. Each division wall is provided with an opening 60 at one end thereof, the adjacent walls having their openings at opposite ends so that the escaping gases are caused to travel from one side to the other of the chamber in the space between each pair of division walls 65 thus taking a course following the coil 17.

These escaping gases, therefore, while following the course of the coil 17 tends to cool every twist or section of the latter, the advantage of which is obvious. The gases when reaching the top of the chamber 16 70 find an exit through an outlet port which communicates with a pipe section 22 the latter leading the gases to other devices (not shown) so that the same may be used for various purposes. 75

In order to retain the chamber at a low temperature to prevent absorption of the heat, this chamber 16 is covered with a very thick layer of magnesia lagging or other non-conductor of heat which is non-combustible. Leading through the lower wall of the chamber 16 is an outlet pipe 23 for the liquefied gas, the same communicating with the chamber or tank 18 and being also covered with the lagging. At the outer end 80 of this pipe 23 is a valve 24 which controls the flow of the liquid through the device. Especially prepared receptacles for containing the liquefied gas for transportation purposes may be connected directly to this pipe 85 section 23, if desired. When it is desired to transport the liquefied gas in small quantities such receptacles are filled directly from this pipe section 23. When, however, it is desired to fill the receptacles with the liquid 90 to be transported in large quantities, a branch pipe section 25 is utilized. This branch pipe section connects with the pipe section 23 and leads to some remote point. This pipe section 25 is also covered with 95 heavy lagging and is provided with a valve 26 and in this connection it is to be noted that all piping exposed to the outside atmosphere and used for the purpose of conveying the gas to be liquefied may, if necessary, be 100 protected by suitable heat insulating material as will be readily understood.

As the cooled gas enters the chamber 16 and passes through the coil 17 and the tank or chamber 18, a portion of the gas is liquefied, the remaining portion passing out through the expansion valve 19 into the chamber 16 where it expands at once from several hundred pounds a square inch to a pound or so above atmospheric pressure. 110 This expansion reduces the temperature of 115 gas below the liquefying point of ethane (C_2H_6) and the higher hydro-carbons such as propane (C_3H_8), butane (C_4H_{10}), etc. This cold gas which is chiefly methane 120 (CH_4), the other hydro-carbons having been condensed out, is led back and forth outside of the coil 17 and thus cools the gas inside of said coil, to a very low temperature. In this manner the hydro-carbons, other than 125 the methane, are condensed out and collected in the chamber or tank 18. A portion of the methane is dissolved in the liquefied gases while the other portion, after being utilized as the cooling medium in the cham- 130

ber 16, passes out therefrom through the pipe 22 to be again utilized for various other purposes, such as lighting, heating, etc. This liquefying process utilizes, as mentioned before the principle of reverse stream inasmuch as the cooling medium (the surplus methane gas) passes outside of the coil in exactly the opposite direction from the gas inside of said coil. In this manner the 10 gas within the coil utilizes practically all of the coldness of the cooling medium which in turn is heated by the gas within the coil and when this cooling medium passes from the chamber 16, it is at substantially the same 15 temperature as the gas which enters at the upper end of the coil 17.

In Figs. 6, 7 and 8 we have shown a modified form of the invention wherein a gas engine 27 is employed to operate a gas compressor 28 the latter receiving gas through an inlet pipe 29. The gas after being compressed is driven through a pair of coolers 30 and 31 respectively which are arranged in spaced relation to one another and are 25 provided with the usual coils. These coils receive the cooling medium, water, from water inlet pipes 32 which communicate with a pump 33.

Leading from the cooling chamber 31 is 30 a conducting pipe 34 which conducts cool gas under high pressure to a gas cooled chamber 35 disposed some distance from the chamber 31. The method of cooling this chamber 35 will be hereinafter and more particularly set forth but arranged therein is a coil 36 which connects at its upper end with the pipe 34 leading through the wall of said chamber. Communicating with the lower end of the coil 36 is a conducting pipe 40 37 which leads through the opposite wall of the chamber 35 and continues on to project through the upper end of an additional air cooled chamber 38. This pipe then connects with an additional coil 39 arranged 45 within the last mentioned chamber, the last mentioned coil at its lower end communicating with a tank or chamber 40 similar to the tank or chamber 18 described in connection with the first mentioned form of the 50 invention. Leading from this tank or chamber 40 is a pipe section 41 which extends through the wall of the chamber 38 and projects through the bottom wall of the chamber 35 to communicate with the interior of the latter. An expansion valve member 42 is provided in the pipe section 41 to enable the unliquefied gases to escape to the interior of the chamber 35. This is similar to the escape of the unliquefied gas referred 60 to in connection with the first mentioned form and it will be seen that this gas entering the lower portion of said chamber 35 will rise to the upper portion thereof to escape through a port 43. This chamber 35, 65 however, is constructed similar to the cham-

ber 16 in the first mentioned form so that this unliquefied gas travels back and forth, following the outline of the coil 36 to thoroughly cool the contents of the latter. The gas after being utilized as a cooling medium 70 in the chamber 35 makes its exit through the port 43 to be utilized again for various other purposes.

Connected with the tank or chamber 40 is an outlet pipe 44 which leads through the 75 bottom of the chamber 38 to permit the liquefied gas to be bottled or tanked for transportation purposes.

As stated above, the chamber 38 is air cooled so that in the liquefaction process, 80 a double cooled system is employed, one a gas and the other an air cooled system. In cooling this chamber 38, an air compressor 45 is employed the same being actuated by means of a gas engine 46. The air compressed is conducted through a pair of cooling members 47 and 48 respectively, the latter being cooled by water pumped from the member 33. The cooled air under heavy pressure is conducted from the cooler 90 48 through a pipe section 49 which leads through the bottom of the chamber 38. An air expansion valve 50 is provided in connection with the pipe section 49 and the air expanding within the chamber 38 tends to 95 cool the coil 39 therein. This chamber 38 is constructed similar to the chamber 35 so that the cooled air under pressure therein follows the course of the coil 39 thoroughly cooling the contents of the latter and finding 100 an exit through a port 51 at the upper end of said chamber 38. If desired the escaping air through the port 51 may be utilized for other purposes.

From the foregoing description of our 105 improved apparatus the manner of applying the same to use and the operation thereof will be readily understood and it will be seen that we have provided a simple, inexpensive and efficient means for carrying out 110 the objects of the invention, and one which may effectively be used in the production of liquid air, as will be readily understood.

All previous commercial attempts have been based on the utilization of portions of 115 gas to liquefy the rest.

While we have particularly described the elements best adapted to perform the functions set forth, it is obvious that various changes in form, proportion and in the 120 minor details of construction may be resorted to, within the scope of the appended claim, without departing from the spirit or sacrificing any of the principles of the invention.

Having thus described our invention, what we claim is:

A device of the class described comprising a closed heat insulated chamber having a zig-zag passage extending therethrough 130

from its upper to its lower end, said passage being provided with an outlet at its upper end, a coil of pipes arranged within said chamber and having its turn following the course of said passage and being provided with an inlet at its upper end, a horizontally extending closed collecting tank arranged in the lower end of said chamber, one of the ends of said tank being connected to the lower end of said coil, an outlet at the other end of said tank extending through said chamber to the exterior thereof, and an expansion valve fixed to the upper side of said tank at its opposite end thereof to provide an exit for the gases collected in the upper portion of the same,

said valve being provided with manually operable means disposed on the exterior of said chamber for operating the same.

In testimony whereof we have hereunto set our hands in presence of two subscribing witnesses.
